CLAIM

The ornamental design for a container stand as shown and described.

DESCRIPTION

FIG. 1 is a front and right side perspective view of a container stand showing our new design;

FIG. 2 is a rear and left side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof; and,

FIG. 9 is a front and right side perspective view thereof, with a medical sharps container mounted therein.

The broken lines in FIG. 9 in shape of a medical sharps container depict environmental subject matter and form no part of the claimed design. The remaining broken lines in

(Continued)

FIGS. 1, 2, 7, and 8 depict portions of the container stand that form no part of the claimed design.

1 Claim, 7 Drawing Sheets
